Primary Examiner—Clare E Heflin

(57) **CLAIM**

The ornamental design for a lighting device housing, as shown and described.

DESCRIPTION

FIG. 1 is a front perspective view of the lighting device housing showing our new design;

FIG. 2 is a rear perspective view thereof;

FIG. 3 is a front view thereof;

FIG. 4 is a right side view thereof;

FIG. 5 is a top view thereof; and,

FIG. 6 is a front perspective view of the lighting device housing showing an alternate view of our new design.
